UNITED STATES PATENT OFFICE

145,558

DESIGN FOR A BUTTON OR SIMILAR ARTICLE

Max Ballot, New York, N. Y.

Application March 23, 1946, Serial No. 127,864

Term of patent 3½ years

(Cl. D17—2)

To all whom it may concern:

Be it known that I, Max Ballot, a citizen of the United States of America, residing in New York city, county of New York, and State of New York, have invented a new, original, and ornamental Design for a Button or Similar Article, of which the following is a specification, reference being had to the accompanying drawing, forming part thereof.

Fig. 1 is a plan view of a button or similar article showing my new design.

Fig. 2 is an edge view thereof.

I claim:

The ornamental design for a button or similar article, substantially as shown.

MAX BALLOT.
